(57) **CLAIM**

The ornamental design for a drink cup lid, as shown and described.

DESCRIPTION

FIG. 1 is a top perspective view of a drink cup lid showing my new design;

FIG. 2 is a bottom perspective view thereof;

FIG. 3 is another bottom perspective view thereof;

FIG. 4 is a side view thereof;

FIG. 5 is a top plan view thereof;

FIG. 6 is a bottom view thereof;

FIG. 7 is an enlarged cross-sectional view thereof, taken along line 7-7 of FIG. 5;

FIG. 8 is an enlarged cross-sectional view thereof taken along line 8-8 of FIG. 5;

FIG. 9 is an enlarged cross-sectional view thereof, taken along line 9-9 of FIG. 5;

FIG. 10 is a top perspective view of another embodiment of a drink cup lid showing my new design;

FIG. 11 is a bottom perspective view thereof;

FIG. 12 is a top perspective view, showing the claimed design independent of the drink cup lid to show aspects of the design not visible when combined;

FIG. 13 is a bottom perspective view thereof;

FIG. 14 is a top plan view thereof;

FIG. 15 is a bottom view thereof the portion included in the drink cup lids of my new design;

FIG. 16 is a side elevation view thereof; and,

FIG. 17 is side elevation view thereof.

The broken lines are shown for the purpose of illustrating parts of the article as well as the designation of enlargement views. None of the broken lines form part of the claimed design.
